UNITED STATES PATENT OFFICE.

OTTO T. SWANSON, OF KINGSTON, ILLINOIS.

DESIGN FOR A RADIOCABINET.

Application filed December 5, 1927. Serial No. 24,379. Term of patent 7 years.

To all whom it may concern:

Be it known that I, OTTO T. SWANSON, a citizen of the United States of America, and a resident of Kingston, in the county of De Kalb, and State of Illinois, have invented a new, original, and ornamental Design for a Radiocabinet, of which the following is a specification, reference being had to the accompanying drawing, forming part thereof.

Figure 1 is a front elevation of a radiocabinet, showing my new design.

Figure 2 is a side elevation thereof, and
Figure 3 is a rear elevation thereof.

I claim:

The ornamental design for a radiocabinet, as shown.

OTTO T. SWANSON.
